LEVER HOT STICK FOR COMPRESSING SLEEVES OR THE LIKE

William F. Turner, Taylorville, Ill., assignor to Boden-
dieck Tool Company, Taylorville, Ill., a corporation
of Illinois

Filed Oct. 24, 1960, Ser. No. 62,579

Term of patent 14 years

(Cl. D54—13)

Fig. 5.

Fig. 6.

FIG. 1 is a side elevational view of a lever hot stick for compressing sleeves or the like embodying my new design;

FIG. 2 is a fragmentary side elevational view on a larger scale of the upper end of the lever hot stick;

FIG. 3 is a top plan view of the same as shown in FIG. 2;

FIG. 4 is a bottom plan view as shown in FIG. 2;

FIG. 5 is a front elevational view thereof, as shown in FIG. 2;

FIG. 6 is a rear elevational view thereof, as shown in FIG. 2;

FIG. 7 is a fragmentary sectional view taken on the plane of the line 7-7 of FIG. 2, looking in the direction of the arrows.

The other side of the hot stick is substantially the same as the side shown in FIG. 1 except that the pivot bolts for the jaws have nuts on the back side of FIG. 1, as

seen at the top of FIG. 3 and bottom of FIG. 4, and left of FIG. 5.

The stippling on the jaw members, as shown in FIGS. 1 and 2, represents contrasting, rough textured surfaces.

The dominant features of the design reside in the fragmentary portion thereof shown in FIGS. 2 through 6 inclusive.

I claim:

The ornamental design for a lever hot stick for compressing sleeves or the like, as shown and described.
